UNITED STATES PATENT OFFICE.

OSCAR H. PIEPER AND ALPHONSE F. PIEPER, OF ROCHESTER, NEW YORK.

INDICATOR MECHANISM.

1,328,895.

Specification of Letters Patent. Patented Jan. 27, 1920.

Application filed December 27, 1915. Serial No. 68,895.

To all whom it may concern:

Be it known that we, OSCAR H. PIEPER and ALPHONSE F. PIEPER, of Rochester, in the county of Monroe and State of New York, have invented certain new and useful Improvements in Indicator Mechanisms; and we do hereby declare the following to be a full, clear, and exact description of the same, reference being had to the accompanying drawings, forming a part of this specification, and to the reference-numerals marked thereon.

Our invention has for its object to provide a novel method of mounting an indicator mechanism, and has reference more particularly to the arrangement of a fluid pressure indicator with reference to a panel board or other support so that the bulk of the device, that is to say, the operating or controlling mechanism may be disposed upon the back or rear side of the support, while the indicator together with the indicating dial and coöperating parts may be arranged upon the front of the support, thus eliminating from the front surface of the panel any unnecessary or large projecting parts such as when the entire mechanism is arranged upon one side. A further purpose of the improvement is to afford a simple arrangement for carrying out the general objects set forth, and so arranging and combining the different portions of the structure as to make it possible to readily assemble them in operative relation upon a support or to remove the mechanism when this becomes desirable; and at the same time, afford rigid retaining means for the indicator. To these and other ends the invention consists in certain improvements and combinations of parts all as will be herein-after more fully described, the novel features being pointed out in the claims at the end of the specification.

In the drawings:

Figure 1 is a plan view showing the application of the invention to a usual type of pressure indicator, with the panel or support broken away;

Fig. 2 is a similar view with parts removed;

Fig. 3 is a vertical sectional view taken transversely, and

Fig. 4 is a sectional view on line 4^a-4^a of Fig. 3.

Similar reference numerals throughout the several views indicate the same parts.

In the arrangement which we have shown 1 indicates a supporting member or wall which may be in the form of a panel constituting part of a controlling mechanism, 60 in connection with which it is desirable to afford an indication of pressure within a system, and without disposing all of the operating parts for the indicating mechanism upon the front of the panel. With this 65 in view, we employ a housing 2 carrying the operating mechanism and supported on the back of the panel 1 by means of bolts 3 which engage a plate 4 on the front of the panel, through which they pass, and having threaded extremities engaging threaded openings in the base of the housing 2. The controlling mechanism includes an expandable member 5 connected with an air passage 6 which terminates in a connection 7 75 to which an air line may be attached. The expandable member 5 is operatively associated with a gear segment 8 which engages a pinion 9 on the arbor 10 and since the operative connection between the fluid expandable member and the arbor 10 form no part of the present invention, it is unnecessary to describe these in any greater detail than above.

The arbor 10 is located in an opening 11 85 in the panel, extending beyond the opposite surfaces of the panel and having the pinion 9 already described, located at its inner extremity. The outer or opposite end of the arbor 10 carries an indicator or hand 12 fixed 90 thereon and coöperating with an indicating dial 13 which is located adjacent the aforementioned plate 4 and within the flange 14 formed around the edge of the latter. 15 is a crystal supporting ring bearing against the crystal 16 which is retained in place by the threaded ring 17 engaging a threaded portion on the edge of the flange 14. The ring 15 rests partly on the flange 14 and partly on the peripheral edge of the dial 13 100 thus serving to hold the latter firmly against the plate 4. To assemble the structure the arbor 10 is inserted through the opening 11 to position the housing 2 which is then secured in place by the bolts 3. The dial plate 105 13 is next arranged over the plate 4, after which the indicator 12 may be attached to the arbor, and the crystal and its coöperating parts can thereafter be secured in place.

The structure which we have described 110 herein affords an extremely simple and unique arrangement that is especially effec-

tive in the relation described. The cost of manufacturing and the difficulty in assembling is no greater than with the ordinary type of indicating mechanism. While the 5 application discloses a more or less specific embodiment of the improvement it will be understood that the invention is intended to cover any arrangement in which is contemplated positioning an indicating member 10 upon one side of a panel or support and operating it from mechanism located on the opposite side of the panel, as well as the particular arrangement described.

We claim as our invention:

- 15 1. In an indicator mechanism, the combination of a supporting member having an opening therethrough, pressure indicator operating mechanism, a housing therefor, a plate having a transversely projecting annular flange, means for securing the housing and plate to opposite sides of the supporting member, an indicator scale supported within the flange on said plate, a threaded ring also supported on said plate, a crystal supported 20 in said ring, a spacing ring bearing against 25 the scale and the inner face of the crystal,

and indicating means coöperating with said indicator scale and controlled by said operating mechanism.

2. In an indicator mechanism, the combination of a panel having an opening therethrough, pressure indicator operating mechanism on one side of the panel, a pressure indicator on the other side of the panel including a plate, means for securing the 30 mechanism and plate to each other with the latter in contact with the panel, operating connections between said mechanism and indicator extending through the panel opening, an outwardly projecting flange on said 40 plate, an indicator scale on said plate within the flange, a spacing ring engaging said scale, a plate of transparent material engaging the spacing ring, and a retaining ring in threaded engagement with said flange and having 45 a shoulder bearing on said transparent plate.

OSCAR H. PIEPER.
ALPHONSE F. PIEPER.
